ONE PIECE PAJAMA GARMENT

George P. Keyloun, 7205 Narrows Ave.,
Brooklyn, N.Y. 11209

Filed Sept. 2, 1966, Ser. No. 3,710

Term of patent 3½ years

(Cl. D2—30)

FIG. 1 is a front perspective view of a one piece pajama garment showing my new design;

FIG. 2 is a front elevational view thereof;

FIG. 3 is a side elevational view, the side opposite being a mirror image thereof; and

FIG. 4 is a rear elevational view.

I claim:

The ornamental design for a one piece pajama garment, substantially as shown and described.
